UNITED STATES PATENT OFFICE

143,571

DESIGN FOR A CASE FOR CIGARETTE AND CIGAR LIGHTER

George C. Beckstein, Buffalo, N. Y., assignor to Star Ring Manufacturing Company, Buffalo, N. Y., a partnership

Application August 3, 1945, Serial No. 121,184

Term of patent 14 years

(Cl. D48—27)

To all whom it may concern:

Be it known that I, George C. Beckstein, a citizen of the United States, residing at Buffalo, in the county of Erie and State of New York, have invented a new, original, and ornamental Design for a Case for Cigarette and Cigar Lighter, of which the following is a specification, reference being had to the accompanying drawing, forming part thereof.

In the drawing:

Fig. 1 is a perspective view of the casing of a cigarette and cigar lighter, embodying my new design and viewed from the top, one side and the rear end thereof.

Fig. 2 is a similar view thereof viewed from the top, the side and the front end of the same.

Fig. 3 is a bottom plan view of the same.

Fig. 4 is a top plan view thereof.

The side of the article opposite to that shown in Figs. 1 and 2 is a duplicate of the side illustrated.

I claim:

The ornamental design for a case for cigarette and cigar lighter, as shown and described.

GEORGE C. BECKSTEIN.
